United States Patent Office

Des. 179,022
Patented Oct. 23, 1956

179,022

BOTTLE

Samuel W. Menefee, Jr., Manheim Township, Lancaster County, Pa., assignor to Armstrong Cork Company, Lancaster, Pa., a corporation of Pennsylvania

Application May 9, 1956, Serial No. 41,408

Term of patent 14 years

(Cl. D58—8)

The single figure is an elevational view of a bottle showing my new design.

The dominant features of my design are shown in full lines in the drawing.

The portions of the bottle not shown are the same as the portions shown.

I claim:

The ornamental design for a bottle, substantially as shown and described.
